(57) **CLAIM**

The ornamental design for a drill, as shown and described.

DESCRIPTION

FIG. 1 is an upper perspective view of the drill showing my design.

FIG. 2 is a top plan view thereof;

FIG. 3 is a bottom plan view thereof;

FIG. 4 is a side elevation view thereof;

FIG. 5 is an opposite side view thereof;

FIG. 6 is a front elevation view thereof;

FIG. 7 is a back elevation view thereof;

FIG. 8 is still another front perspective view thereof; and, FIG. 9 is a perspective view, showing the drill mounted in an injection mechanism for positioning the drill, wherein the injection mechanism is shown in broken lines.

The broken line features are presented for illustrative purposes and form no part of the claimed design.
